UNITED STATES PATENT OFFICE.

BENSON N. WINEGARDEN, OF PITTSBURGH, PENNSYLVANIA.

ELECTRIC-CIRCUIT CONTROLLER.

Application filed June 23, 1927. Serial No. 200,807.

My invention relates to electric circuit controllers or electric current distributing devices designed primarily for flashing electric signs, but it may be applied to other 5 uses.

It is one object of this invention to provide a drum-type of current controller or distributor which is simple in construction and can be readily assembled to provide the 10 drum with annular series of blocks, some or all of which in each series may be electric contacts, the remainder being insulators. Each series will have its blocks grouped or spaced so that the brush riding thereon will 15 close or open circuits for displaying or cutting out certain electric lamps, as may be required to produce predetermined signs, letters, figures, etc.

Another object is to provide for the accommodation of a variable number of such 20 series on the drum.

Another object is to provide novel means for spacing the several series of blocks and holding them in place.

25 Other objects appear hereinafter.

Referring to the accompanying drawing, Fig. 1 is a side elevation of my invention; Fig. 2, a section on the line II—II of Fig. 1; and Fig. 3, a section on the line III—III of 30 Fig. 1.

On the drawings, 1 designates the base member of a frame having the two upstanding end members 2 in which the shaft 3 which supports the drum 4 is mounted to 35 rotate. The shaft is driven by the pinion 4'.

The drum is made of good conducting material, as copper, and is preferably hollow. Its periphery has a series of parallel T-shaped grooves 5 running longitudinally 40 thereof. For these grooves I provide three kinds of blocks, marked 6, 7 and 8, respectively. The blocks 6 and 7 are H-shaped in cross-section, the blocks 6 being contacts and composed of copper or other good conducting material, and the blocks 7 being composed of fibre or other non-conducting material. The blocks 8 are flat and composed of fibre or other non-conductor.

The blocks 6 and 7 are slid along the 45 grooves 5 and assembled into a number of annular series 9, 10, 11, 12, and 13, on which the brushes 14, 15, 16, 17 and 18 respectively ride, the brushes being pivoted on the non-conducting rod 19 supported by the end 50 members 2 of the frame. The T-shaped grooves 5 have their heads facing the axis

of the drum. One of the parallel members of each block is slid into the head part of a groove 5 with the cross member of the H-shaped block in the outwardly extending 60 leg-member of the T-shaped groove. The remaining of the parallel members of each block lies just beyond the periphery of the drum. The blocks in each series are held in selected spaced relation from the blocks in the adjacent series by the flat fibre blocks 8 which are slid in the head members of the T-shaped grooves 5. Blocks 8 also are placed in the grooves 5 against the outer ends of the end series 9 and 13 to hold the latter in 65 place.

The wire 20 feeds current to the brush 14 and the wires 21, 22, 23 and 24 conduct away the current to predetermined devices, as flash signals or signs, as each contact block 6 engages its proper brush. Current coming in on the wire 20 will pass through the brush 14 and certain of the contact blocks 6 of the series 9 and into the drum 4. As the drum rotates current will flow from the drum through the various contacts 6 as they engage the various brushes, whence the current goes out on the wires 20 to 24 to predetermined translating devices, such as electric lamps.

70 The contacts 6 and the insulators 7 will be arranged in each series to bring the current to the proper brushes and to maintain the current there the length of time desired. The blocks, 6, 7, and 8 can be made longer 75 or shorter so as to provide for a maximum or a minimum number of annular series, or for any intermediate number.

I claim:

1. In an electric current controller, a rotary drum having continuous peripherally-open grooves extending longitudinally thereof, the grooves being enlarged at their bottoms, a plurality of annular series of blocks each having enlarged ends connected 90 by a web, one of the enlarged ends and the web of each block being in a groove and the other of the enlarged ends being external of the drum, and some of the blocks being of conducting material and constituting contacts, insulating spacing blocks in the grooves between successive series of blocks, and a brush arranged to be engaged by each of the series of blocks as the drum rotates.

2. In an electric current controller, a rotary drum having continuous peripherally-open grooves extending longitudinally

thereof, the grooves being enlarged at their bottoms, a plurality of annular series of blocks each having enlarged ends connected by a web, one of the enlarged ends and the web of each block being in a groove and the other of the enlarged ends being external of the drum, and some of the blocks being of conducting material and constituting contacts, insulating spacing blocks slidable in

the grooves between successive series of blocks and against the outer ends of the blocks in the terminal series, and a brush arranged to be engaged by each of the series of blocks as the drum rotates.

In testimony whereof I hereunto affix my ¹⁰ signature.

BENSON N. WINEGARDEN.
